UNITED STATES PATENT OFFICE.

ALBERT M. BAKER, OF LEXINGTON, KENTUCKY.

ELLURIAN.

SPECIFICATION forming part of Letters Patent No. 642,835, dated February 6, 1900.

Application filed April 26, 1899. Serial No. 714,572. (No model.)

To all whom it may concern:

Be it known that I, ALBERT M. BAKER, a citizen of the United States, residing at Lexington, in the county of Fayette and State of Kentucky, have invented a new and useful Tellurian, of which the following is a specification.

My invention relates to tellurians, and has for its object to simplify and improve the mechanism shown and described in my former patent, No. 610,317, granted to me on September 6, 1898, the said mechanism being designed for illustrating the movement of the sun in its orbit and its axial rotation, for illustrating the diurnal rotation of the earth and its movement around the sun in its elliptical orbit, for illustrating the normal inclination of the earth's axis to the plane of the ecliptic, for illustrating the axial rotation of the moon and its movement around the earth and sun, for illustrating the variation of the plane of the moon's orbit from that of the ecliptic and the variation of the inclination of the moon's axis with relation to that of the earth, and for illustrating the location of the sun in the northern focus of the earth's orbit.

Further objects and advantages of this invention will appear in the following description, and the novel features thereof will be particularly pointed out in the appended claims.

In the drawings, Figure 1 is a side view, partly in section, of a tellurian constructed in accordance with my invention. Fig. 2 is a plan view of the same, showing in dotted lines the positions of the parts when the supporting-arm has made a quarter-revolution from the position illustrated in full lines. Fig. 3 is a detail sectional view of the mechanism for operating the supporting-arm and the sun-globe spindle and for causing the elliptical orbit of the earth. Fig. 4 is a detail sectional view of the mechanism arranged at the outer end of the orbital arm. Fig. 5 is a detail sectional view of the moon-globe-carrying collar and adjacent parts. Fig. 6 is a similar view of the slide and guide by which the elliptical movement of the orbital arm is caused.

Similar reference characters indicate corresponding parts in all the figures of the drawings.

1 designates a base which is superficially

inscribed or otherwise marked to represent an elliptical zodiac 2, including characters representing periods of time, such as the seasons, the months, and days. This base may constitute the top of a table having legs or supports 1^a, of channel-iron or the equivalent thereof, removably attached at their upper ends to cleats 1^b, also of channel-iron, and 55 having terminal angularly-disposed portions 1^c, forming seats for the reception of the upper ends of the legs or standards. In the construction illustrated said legs are secured in the seats by means of bolts 1^d.

Depending from the base at an intermediate point is a spindle 3, upon which is mounted a sleeve 4 on the adjacent end of a supporting-arm 5, and this supporting-arm is provided at its free end with a vertical spindle 6, which extends upward through a segmental slot 7, formed in the base concentric with the spindle 3 and designed to allow a limited oscillatory movement of the supporting-arm. Fixed to the spindle 6 at its upper 70 extremity is a sun-globe-supporting plate 8, provided with a collar 9, having a set-screw 10 by which the plate may be locked in place to follow the movements of the spindle 6. In a bearing 11, formed near the outer end of 80 said plate 8, is mounted the sun-globe spindle 12, having a collar 13, held in place by a set-screw 14 and adapted to bear upon the upper end of the bearing 11 to prevent downward axial displacement of the spindle. The 85 sun-globe 15 is provided with a collar 16, fitted upon the upper ends of the sun-globe spindle and provided with a set-screw 17, by which it may be secured in place. To the lower end of the sun-globe spindle is affixed 90 a pulley 18, connected by a belt 19 or other endless connection with a pulley 20, arranged concentric with the spindle 6. To conceal the pulleys and belt, the sun-globe-supporting plate 8 is provided near its periphery 95 with a depending guide-flange 21.

Mounted upon the spindle 6 for independent revoluble movement is the hub or sleeve 22 of an orbital arm 23, said sleeve or hub 22 being of sufficient length to extend downward through the slot 7 in the base, where it carries a radial arm 24, secured in place by means of a set-screw 25. This radial arm, which is arranged in the vertical plane of the

orbital arm, is provided with a pin 26, engaged with a slide or traveler 27, mounted for reciprocatory movement in a parallel-sided guide 28 29, of which the parts are disposed upon opposite sides of the slot 7 and are secured to the under side of the base. The slide or traveler is adapted to move from one of the members of the guide across the slot 7 and into the other member of the guide 10 during the rotary movement of the orbital arm 23 around the spindle 6 as its axis, and as the slide or traveler operates in a fixed guide it is obvious that while the spindle 6 will be in the plane of the guide when the 15 orbital arm extends parallel with the major axis of the earth's orbit, as indicated in Fig. 2, the movement of the orbital arm to a position such as that indicated in dotted lines in Fig. 2 will cause the spindle 6 to move 20 westward, and thereby cause the movement of an earth-globe, supported by said orbital arm, to travel in an elliptical path.

Fixed to the spindle 6, and hence held in a stationary position with relation to the supporting-arm, is a gear 30, a set-screw 31 being employed to facilitate the attachment of said gear, and mounted, preferably, in depending bearings 32 and 33 on the orbital arm is an operating-spindle 34, having a pinion 35, which meshes with the gear 30, whereby as the orbital arm 23 swings around the carrying-spindle 6 rotary motion is communicated to the operating-spindle 34. A dust-guard 36, which is mounted upon the inner 35 end of the orbital arm, serves the double function of protecting the gearing and of supporting the pulley 20, and the orbital arm is preferably provided with a depending guard-flange 37 for a purpose analogous to that described in connection with the sun-globe-supporting plate. Near its outer end the orbital arm is provided with an enlargement, forming a sleeve 38, in which is secured a tubular or hollow bearing 39, and within this 45 tubular bearing is mounted an earth-globe-carrying spindle 40, provided at its lower end with a gear 41, with which meshes a pinion 42, carried by the operating-spindle 34. To the upper end of this earth-globe-carrying 50 spindle is fixed the hub or sleeve 43 of an earth-globe-carrying plate 44, having a depending guard-flange 45, a set-screw 46 being employed to secure said plate in a fixed position with relation to the spindle and a similar set-screw 47 being employed in connection 55 with the gear 41 for a similar purpose. Also mounted exteriorly upon the tubular bearing 39 is a sleeve 48, forming a hollow or tubular spindle, to the lower end of which is 60 fixed a gear 49, which also meshes with a pinion 42 from the opposite side of the gear 41, whereby during the movement of the operating-spindle the gears 41 and 49 are rotated in opposite directions or for a purpose herein- 65 after explained. Said sleeve 48 carries a pulley 50, which is connected by a belt 51 with a pulley 52 on an earth-globe spindle 53,

whereby rotary motion may be communicated from the operating-spindle 34 through the intermeshing gears 42 and 49 to the sleeve 48, 70 and thence through the belt-gearing to the earth-globe-spindle, while rotary motion in the opposite direction is communicated from the same spindle 34 through the gears 42 and 41 to the spindle 40 to cause rotation of the 75 earth-globe-carrying plate 44 in a direction opposite to that of the earth-globe spindle.

The means for demonstrating the phenomena dependent upon the inclination of the axis of the earth-globe 54, whereby said inclination may be changed to illustrate the effect which would be produced thereby upon the seasons, are substantially identical with means for a similar purpose shown and described in my former patent above mentioned, 80 and include a flexible earth-globe spindle having an upper section 53^a, connected by a knuckle-joint with the lower or main section, said angularly-movable section having the earth-globe attached thereto, a cup 55, carried 85 by the earth-globe-supporting plate 44 and provided with a plurality of seats 56, arranged at different inclinations around the main section of the earth-globe spindle, and a spindle 57, mounted to slide upon the upper earth-globe-spindle section and adapted to fit in 90 either of said seats to maintain said upper earth-globe-spindle section in any one of a plurality of positions. In the construction illustrated, however, the parts are so related 95 that when the upper earth-globe-spindle section is in its normal position, whereby the axis of the earth-globe is inclined in the proper direction and correct angle toward the north, the center of the earth-globe is directly 100 over the center of the earth-globe-carrying spindle 40. In the construction illustrated in my former patent above named the center of the earth-globe was located south of the earth-globe-carrying spindle for the purpose 105 of illustrating the arrangement of the sun-globe in the northern focus of the earth's orbit, but in the present construction the illustration of the location of the sun-globe in the northern focus of the earth's orbit is accomplished by disposing the sun-globe spindle in 110 a position north of the axis of movement of the orbital arm 23.

Mounted to slide-axially upon the sleeve 48 is a collar 58, which is keyed to said sleeve 115 to cause simultaneous rotation thereof or, in other words, to allow independent axial sliding movement of the collar while adapting the sleeve to communicate rotary motion to the collar. In the construction illustrated radial pins or screws 59 project from the collar into longitudinal slots 60 in the sleeve. Also mounted for axial sliding movement upon the sleeve 48 is a thimble 61, having a swivel connection with the collar 58, by means of pins 120 or screws 62, fitting in an annular groove 63, formed in the outer side of the collar. The collar carries the moon-globe-supporting arm 64, to the extremity of which is affixed the

moon-globe 65, and it will be understood from the foregoing description that by communicating reciprocatory motion to the thimble 61 the collar 58, with the moon-globe supporting arm, will be correspondingly reciprocated, while rotary motion to the collar may be communicated from the sleeve 48, which is the means for communicating rotary motion to the earth-globe spindle.

The means which I have illustrated in the drawings for communicating reciprocatory motion to the thimble 61 include a crank 66, formed in the operating-spindle 34 and connected by a pitman 67 with a wrist-pin 68 on the thimble, and, preferably, said wrist-pin operates in a slot 69, formed in a vertical guide 70, which rises from a dust cap or guard 71, carried by the orbital arm to inclose the crank and adjacent gears. This combined reciprocatory and rotary movement of the moon-globe-carrying collar 58 produces the orbital movement of the moon-globe around the earth-globe and at the same time the inclination of the plane of the moon-globe orbit to that of the ecliptic, such inclination being about five degrees. In addition, however, to the above-described movements of the moon-globe it has an axially-tilting movement consisting in an inclination of the upper end of its axis toward the earth-globe at one portion of the moon's orbit and an opposite movement, or away from the earth, at another portion of its orbit. To accomplish this tilting movement, I employ a rocker 72, consisting of a rim or band which encircles the upper portion of the collar 58 and is provided with fulcrum-pins consisting of the guide-screws 59, and said rocker being sufficiently loose upon the collar to allow a tilting movement downward for illustrating an axial inclination of about one and one-half degrees of the moon-globe axis. This rocker is provided with a radial stem 73, upon which is fitted a socket 74 at the inner end of the moon-globe-supporting arm 64. Also the sleeve 48 is provided with a longitudinal cam 75, formed, in the construction illustrated, by longitudinally channeling the sleeve and providing the channel with an inclined or beveled floor, and carried by the rocker in operative relation with this cam is a finger 76. Thus during the downward movement of the moon-globe-carrying collar the finger 76 is forced outward by the cam 75 to cause an upward-swinging movement of the moon-globe-supporting arm, and hence the tilting of the upper end of the moon-globe axis toward the earth, whereas during the movement of the moon-globe-carrying collar in an upward position the reverse operation is produced to cause the tilting of the moon-globe axis in a direction away from the earth.

The sun's axis is inclined at an angle of about eight degrees toward that part of the earth's orbit which the earth occupies in September, and in order that the center of the sun-globe shall be directly above a line drawn

on the earth's orbit from about the 21st of June to the 21st of December, said line passing directly through the center of movement 70 of the orbital arm when the parts are in the positions indicated in Fig. 1 and in full lines in Fig. 2, the sun-globe-supporting plate is extended from the spindle 6 in a direction westward from said line connecting the June 75 and December points of the earth's orbit, whereby a line connecting the centers of the spindles 6 and 12 if extended will touch that part of the orbit which the earth occupies between the 15th and 20th of January. This 80 disposition of the plate 8 throws the bottom of the spindle 12 sufficiently far toward that part of the orbit occupied by the earth in March to allow the inclination of the spindle 12 to dispose the center of the sun-globe directly over the line connecting the June and December points of the earth's orbit, and hence accurately locates the sun-globe in the northern focus of said orbit.

From the above description it will be seen 90 that I have dispensed with much of the gearing illustrated in a former patent above mentioned and at the same time have accomplished all of the necessary movements of the three celestial bodies represented. The sun-globe receives an orbital and also a rotary movement upon its axis, the latter motion being due to the operation of the pulley 20, caused by the rotation of the orbital arm 23 about the spindle 6 as a center. Furthermore, said swinging movement of the orbital arm causes the shifting of its axis in a direction transverse to the major axis of the ellipse or orbit described by the earth to produce said elliptical motion. Furthermore, the revolution of the gears 41 and 49 in opposite directions, the latter being backward while the former is forward, causes the earth-globe-carrying plate 44 to swing through one complete backward rotation while the orbital 100 arm 23 describes one complete forward rotation, and hence the inclination of the earth's axis remains constant or uniform, or, in other words, the earth's axis remains parallel with itself throughout the orbital movement of the 115 earth-globe. The earth-globe spindle, however, receives a forward rotation to produce the diurnal revolution of the earth-globe, its direction of rotation corresponding with that of the earth.

In practice I prefer to construct the gear 49 with one or two teeth more than the gear 41, and hence it follows that when the orbital arm has completed one forward revolution and the gear 41, which occupies the earth-globe-carrying spindle, has completed one backward rotation the gear 49 has not quite completed one revolution, and hence the moon-globe has not quite completed one forward revolution around the earth-globe. 130 Thus at every revolution of the orbital arm the moon-globe will fall a little more behind in its path around the earth to illustrate the movement of the earth's orbit and the moon's

nodes from east to west or backward, or, in other words, causes a retrogressive movement of the moon's nodes.

It will be seen that in the above description I have made a distinction between the "earth-globe-carrying spindle" 40 and the "earth-globe spindle" 53 for the reason that while the former carries the earth-globe and by its linear movement determines the orbital movement of the earth-globe the latter constitutes the axial support of the earth-globe and controls the axial movement and position thereof.

When the orbital arm 23 is in the position shown in Fig. 1 and the position shown in full lines in Fig. 2, the orbital arm 23 and the supporting-arm 5 are in alinement, or both are in the same vertical plane; but when the orbital arm 23 swings forward toward the position shown by the dotted line in Fig. 2 the supporting-arm 5 swings backward and westward toward its position shown in dotted line and near the end of slot 7 in Fig. 2. The arm 23 will be at right angles to arm 5 slightly before the center of the earth-globe has passed through a quadrant of its orbit or the falling back of arm 5 has caused arm 23 to move more slowly than it would have done had arm 5 remained stationary. While arm 23 is moving forward from its position at right angles to arm 5 the last-named arm is swinging slowly back to its first position, so that when the center of the earth-globe has reached the northern end of the major axis of the earth's orbit the arm 5 has assumed its first position and arms 23 and 5 are in the same vertical plane. Thus the movement of arm 5 has caused arm 23 to move more rapidly in the second interval than it would have done had arm 5 remained stationary. For the same reason arm 23 will move more rapidly through the third quadrant and more slowly through the fourth, or the earth-globe is caused to move more rapidly in that half of its orbit from September to March than it moves in the half from March to September.

In practice it will be understood that various changes in the form, proportion, size, and minor details of construction within the scope of the appended claims may be resorted to without departing from the spirit or sacrificing any of the advantages of the invention.

Having described my invention, what I claim is—

1. A tellurian having a swinging orbital or earth-globe-carrying arm, swinging vibratory mechanism for shifting the axis of said arm in a direction transverse to the major diameter of the orbit described by the earth-globe and means for connecting said devices, substantially as specified.

2. A tellurian having a swinging orbital or earth-globe-carrying arm, a transversely-movable spindle therefor, a reciprocator traveler, and a swinging connection between the spindle, orbital arm and the traveler for causing vibratory movement of said spindle, substantially as specified.

3. A tellurian having a base, a swinging orbital or earth-globe-carrying arm, a spindle mounted for vibratory movement in a path transverse to the major diameter of the earth's orbit and adapted to support the said arm, a fixed guide supported by the base, a traveler mounted in said guide, and an arm carried by the orbital arm and having a pivotal connection with said traveler, substantially as specified.

4. A tellurian having a swinging supporting-arm provided with a terminal spindle, an orbital or earth-globe-carrying arm mounted upon said spindle of the supporting-arm, and means for causing a vibratory movement of the supporting-arm during the swinging movement of the orbital arm about its axis, substantially as specified.

5. A tellurian having a swinging supporting-arm provided with a terminal spindle; an orbital or earth-globe-carrying arm mounted for swinging movement upon said spindle, a fixed guide parallel with the major diameter of the earth-globe orbit, a traveler mounted in said guide, and an arm connecting the said orbital arm with the traveler, for causing swinging movement of the supporting-arm, substantially as specified.

6. A tellurian having a swinging supporting-arm provided with a terminal spindle, an orbital or earth-globe-carrying arm mounted upon said spindle of the supporting-arm, means for causing a vibratory movement of the supporting-arm during the swinging movement of the orbital arm about its axis, and a sun-globe-carrying plate fixed to the spindle of the supporting-arm, substantially as specified.

7. A tellurian having a swinging supporting-arm provided with a terminal spindle and also having a supporting-plate, an orbital or earth-globe-carrying arm mounted upon said spindle of the supporting-arm, means for causing a vibratory movement of the supporting-arm during the swinging movement of the orbital arm about its axis, and a sun-globe spindle mounted upon said plate eccentrically with relation to the spindle of the supporting-arm, substantially as specified.

8. A tellurian having a swinging supporting-arm provided with a terminal spindle and also having a supporting-plate, an orbital or earth-globe-carrying arm mounted upon said spindle of the supporting-arm, means for causing a vibratory movement of the supporting-arm during the swinging movement of the orbital arm about its axis, a sun-globe spindle mounted upon said plate eccentrically with relation to the spindle of the supporting-arm, and means actuated by the orbital arm for communicating rotary motion to the sun-globe spindle, substantially as specified.

9. A tellurian having a swinging supporting-arm provided with a terminal spindle, an orbital or earth-globe-carrying arm mounted upon said spindle of the supporting-arm,

means for causing a vibratory movement of the supporting-arm during the swinging movement of the orbital arm about its axis, a sun-globe-carrying plate fixed to the spindle of the supporting-arm, and a sun-globe spindle mounted upon said plate at an inclination to the plane of the ecliptic, substantially as specified.

10. A tellurian having a swinging supporting-arm provided with a terminal spindle, an orbital or earth-globe-carrying arm mounted upon said spindle of the supporting-arm, means for causing a vibratory movement of the supporting-arm during the swinging movement of the orbital arm about its axis, a sun-globe-carrying plate and an inclined sun-globe spindle mounted upon said plate and carrying a sun-globe, whereby when the earth-globe is in its summer solstice, the center of the sun-globe is vertically above the northern focus of the orbit of the earth-globe, substantially as specified.

11. A tellurian having a swinging supporting-arm provided with a terminal spindle, an orbital or earth-globe-carrying arm mounted upon said spindle of the supporting-arm, means for causing a vibratory movement of the supporting-arm during the swinging movement of the orbital arm about its axis, a sun-globe-carrying plate fixed to said spindle of the supporting-arm and provided with a bearing which is positioned on a line bearing westward from that of the orbital arm, and a sun-globe spindle mounted in said bearing of the plate and inclined eastward toward its upper end, substantially as specified.

12. A tellurian having a swinging supporting-arm provided with a terminal spindle, an orbital or earth-globe-carrying arm mounted upon said spindle of the supporting-arm, means for causing a vibratory movement of the supporting-arm during the swinging movement of the orbital arm about its axis, a sun-globe-carrying plate fixed to said spindle of the supporting-arm, a sun-globe spindle mounted in a bearing in said plate, pulleys carried respectively by the orbital arm and said sun-globe spindle, and a belt traversing the pulleys, substantially as specified.

13. A tellurian having a swinging supporting-arm provided with a terminal spindle, an orbital or earth-globe-carrying arm mounted upon said spindle of the supporting-arm, means for causing a vibratory movement of the supporting-arm during the swinging movement of the orbital arm about its axis, a sun-globe-carrying plate fixed to said spindle of the supporting-arm, a sun-globe spindle mounted in a bearing in said plate, earth-globe-operating mechanism including an operating-spindle mounted upon said orbital arm, a gear fixed to said spindle of the supporting-arm and meshing with a pinion on said operating-spindle, a dust-guard fixed to the orbital arm to cover said gears, pulleys carried respectively by the sun-globe spindle and said dust-

guard, and a belt traversing the pulleys, substantially as specified.

14. A tellurian having a swinging orbital arm, an operating-spindle mounted upon said arm, means for communicating rotary motion to said spindle, an earth-globe-carrying spindle mounted upon the orbital arm and connected with said operating-spindle for rotation in one direction, a reciprocating traveler, a swinging connection between the spindle of said orbital arm and the traveler, a second spindle concentric with the earth-globe-carrying spindle connected with the operating-spindle for rotation in the opposite direction, an earth-globe-carrying plate carried by said earth-globe-carrying spindle, and an earth-globe spindle mounted upon the earth-globe-carrying plate and operatively connected with said second spindle, substantially as specified.

15. A tellurian having a swinging orbital arm, an operating-spindle mounted upon said arm, means for communicating rotary motion to said spindle, an earth-globe-carrying plate, an earth-globe spindle mounted upon said plate, concentric spindles respectively connected with said plate and the earth-globe spindle and connected with said operating-spindle for simultaneous rotation in opposite directions, a reciprocating traveler, and a swinging connection between the spindle of the orbital arm and the traveler, substantially as specified.

16. A tellurian having a swinging orbital arm, an operating-spindle mounted upon said arm, means for communicating rotary motion to said spindle, a reciprocating traveler, and a swinging connection between the spindle of the orbital arm and the traveler, an earth-globe-carrying plate, an earth-globe spindle mounted upon said plate, concentric spindles connected respectively with said plate and the earth-globe spindle and provided with gears, and a pinion carried by the operating-spindle and meshing at opposite sides with said gears, for communicating rotary motion in opposite directions to said concentric spindles, substantially as specified.

17. A tellurian having a swinging orbital arm, an operating-spindle mounted upon said arm, means for communicating rotary motion to said spindle, an earth-globe-carrying plate, an earth-globe spindle mounted upon said plate, an earth-globe-carrying spindle to which said plate is fixed, and which is operatively connected with the operating-spindle for maintaining a uniform direction of inclination of the axis of the earth-globe, a second spindle also actuated by said operating-spindle, and operatively connected with the earth-globe spindle for communicating diurnal revolution to the latter, a moon-globe-carrying member feathered upon said second spindle for movement parallel with the axis thereof, and means for imparting reciprocating movement to said member, substantially as specified.

18. A tellurian having a swinging orbital arm, an operating-spindle mounted upon said arm, means for communicating rotary motion to said spindle, an earth-globe-carrying plate, 5 an earth-globe spindle mounted upon said plate, an earth-globe-carrying spindle to which said plate is fixed, and which is operatively connected with the operating-spindle for maintaining a uniform direction of incli- 10 nation of the axis of the earth-globe, a second spindle also actuated by said operating-spindle, and operatively connected with the earth-globe spindle for communicating diurnal revolution to the latter, a moon-globe-carrying 15 collar feathered upon said second spindle for movement parallel with the axis thereof, and means actuated by the operating-spindle for reciprocating said collar, substantially as specified.

19. A tellurian having a swinging orbital arm, an operating-spindle mounted upon said arm, means for communicating rotary motion to said spindle, an earth-globe-carrying plate, an earth-globe spindle mounted upon said 25 plate, an earth-globe-carrying spindle to which said plate is fixed, and which is operatively connected with the operating-spindle for maintaining a uniform direction of incli- 30 nation of the axis of the earth-globe, a second spindle also actuated by said operating-spindle, and operatively connected with the earth-globe spindle for communicating diurnal revolution to the latter, a moon-globe-carrying 35 collar feathered upon said second spindle for movement parallel with the axis thereof, and means, including a crank actuated by the operating-spindle, and a pitman between said crank and the collar, for reciprocating the collar upon said second spindle, substantially 40 as specified.

20. A tellurian having a swinging orbital arm, an operating-spindle mounted upon said arm, means for communicating rotary motion to said spindle, an earth-globe-carrying plate, 45 an earth-globe spindle mounted upon said plate, an earth-globe-carrying spindle to which said plate is fixed, and which is operatively connected with the operating-spindle for maintaining a uniform direction of incli- 50 nation of the axis of the earth-globe, a second spindle also actuated by said operating-spindle, and operatively connected with the earth-globe spindle for communicating diurnal revolution to the latter, a moon-globe-carrying 55 collar feathered upon said second spindle for movement parallel with the axis thereof, a sleeve having a swivel connection with said collar and provided with a wrist-pin, a crank actuated by the operating-spindle, and a pit- 60 man connecting said crank with the wrist- pin, substantially as specified.

21. A tellurian having a swinging orbital arm, an operating-spindle mounted upon said arm, means for communicating rotary motion 65 to said spindle, an earth-globe-carrying plate, an earth-globe spindle mounted upon said

plate, an earth-globe-carrying spindle to which said plate is fixed, and which is operatively connected with the operating-spindle for maintaining a uniform direction of incli- 70 nation of the axis of the earth-globe, a second spindle also actuated by said operating-spindle, and operatively connected with the earth-globe spindle for communicating diurnal revolution to the latter, a moon-globe-carrying 75 collar feathered upon said second spindle for movement parallel with the axis thereof, a sleeve having a swivel connection with said collar and provided with a wrist-pin, a crank actuated by the operating-spindle, a 80 pitman connecting said crank with the wrist- pin, and a fixed guide carried by the orbital arm for maintaining said sleeve in a fixed position with relation to the orbital arm, sub- 85 substantially as specified.

22. A tellurian having a swinging orbital arm, an operating-spindle mounted upon said arm, means for communicating rotary motion to said spindle, an earth-globe-carrying plate, an earth-globe spindle mounted upon said 90 plate; an earth-globe-carrying spindle to which said plate is fixed, and which is operatively connected with the operating-spindle for maintaining a uniform direction of incli- 95 nation of the axis of the earth-globe, a second spindle also actuated by said operating-spindle, and operatively connected with the earth-globe spindle for communicating diurnal revolution to the latter, a moon-globe-carrying 100 collar feathered upon said second spindle for movement parallel with the axis thereof, a sleeve having a swivel connection with said collar and provided with a wrist-pin, a crank actuated by the operating-spindle, and a slotted 105 guide carried by the orbital arm and having said wrist-pin arranged therein for recip- 110 rocatory movement parallel with the axis of said second spindle, substantially as specified.

23. A tellurian having a swinging orbital arm, an operating-spindle mounted upon said arm, means for communicating rotary motion to said spindle, an earth-globe-carrying plate, an earth-globe spindle mounted upon said plate, an earth-globe-carrying spindle to which said plate is fixed, and which is operatively connected with the operating-spindle for maintaining a uniform direction of incli- 115 nation of the axis of the earth-globe, a second spindle also actuated by said operating-spindle, and operatively connected with the earth-globe spindle for communicating diurnal revolution to the latter, a moon-globe-carrying 120 collar mounted upon said second spindle for movement parallel with the axis thereof, means actuated by said operating-spindle for reciprocating said collar, a moon-globe-sup- 125 porting arm pivotally mounted upon said collar, and means for oscillating said supporting arm, substantially as specified.

24. A tellurian having a swinging orbital 130 arm, an operating-spindle mounted upon said arm, means for communicating rotary mo-

tion to said spindle, an earth-globe-carrying plate, an earth-globe spindle mounted upon said plate, an earth-globe-carrying spindle to which said plate is fixed, and which 5 is operatively connected with the operating-spindle for maintaining a uniform direction of inclination of the axis of the earth-globe, a second spindle also actuated by said operating-spindle, and operatively connected with 10 the earth-globe spindle for communicating diurnal revolution to the latter, a moon-globe-carrying collar mounted upon said second spindle for movement parallel with the axis thereof, means actuated by said operating-spindle for reciprocating said collar, a rocker mounted upon said collar, means for tilting 15 said rocker during the reciprocatory movement of said collar, and a moon-globe-supporting arm carried by the rocker, substantially as specified.

25. A tellurian having a swinging orbital arm, an operating-spindle mounted upon said arm, means for communicating rotary motion to said spindle, an earth-globe-carrying plate, 25 an earth-globe spindle mounted upon said plate, an earth-globe-carrying spindle to which said plate is fixed, and which is operatively connected with the operating-spindle for maintaining a uniform direction of inclination 30 of the axis of the earth-globe, a second spindle also actuated by said operating-spindle, and operatively connected with the earth-globe spindle for communicating diurnal revolution to the latter, a moon-globe-carrying collar mounted upon said second spindle for movement parallel with the axis thereof, means actuated by said operating-spindle for reciprocating said collar, a rocker mounted upon said collar, a finger carried by 35 the rocker and arranged in operative relation with a cam which occupies a fixed position with relation to the reciprocatory movement of the collar, and a moon-globe-supporting arm carried by the rocker, substantially as 40 specified.

26. A tellurian having a swinging orbital arm, an operating-spindle mounted upon said arm, means for communicating rotary motion to said spindle, an earth-globe-carrying 50 plate, an earth-globe spindle mounted upon said plate, an earth-globe-carrying spindle to which said plate is fixed, and which is operatively connected with the operating-spindle for maintaining a uniform direction of inclination 55 of the axis of the earth-globe, a second spindle also actuated by said operating-spindle, and operatively connected with the earth-globe spindle for communicating diurnal revolution to the latter, a moon-globe- 60 carrying collar mounted upon said second spindle for movement parallel with the axis thereof, means actuated by said operating-spindle for reciprocating said collar, a rocker mounted upon said collar and having a finger, a cam on said second spindle traversed by the finger, for tilting the rocker during the

reciprocatory movement of the collar, and a moon-globe-supporting arm carried by the rocker, substantially as specified.

27. A tellurian having a swinging orbital 70 arm, an operating-spindle mounted upon said arm, means for communicating rotary motion to said spindle, an earth-globe-carrying plate, an earth-globe spindle mounted upon said plate, an earth-globe-carrying spindle to which 75 said plate is fixed, and which is operatively connected with the operating-spindle for maintaining a uniform direction of inclination of the axis of the earth-globe, a second spindle also actuated by said operating-spindle, and 80 operatively connected with the earth-globe spindle for communicating diurnal revolution to the latter, a moon-globe-carrying collar mounted upon said second spindle for movement parallel with the axis thereof, means actuated by said operating-spindle for reciprocating said collar, a rocker mounted upon said collar, means for tilting the rocker during the reciprocatory movement of the collar, a stud projecting radially from the rocker, and a 85 moon-globe-supporting spindle having a socket engaged with said stud, substantially as specified.

28. A tellurian having an orbital earth-globe-carrying arm, and means for causing a 95 swinging movement of said arm at a varying rate of speed in different portions of its path, substantially as specified.

29. A tellurian having a swinging supporting-arm provided with a terminal spindle, an orbital or earth-globe-carrying arm mounted for swinging movement upon said spindle, a fixed guide parallel with the major diameter of the earth-globe orbit, a traveler mounted in said guide, and an arm connecting the said 100 orbital arm with the traveler, for causing swinging movement of the orbital arm at a varying rate of speed, substantially as specified.

30. A tellurian having a swinging orbital 110 arm, an operating-spindle mounted upon said arm, means for communicating rotary motion to said spindle, a reciprocatory traveler having swinging connection with the spindle of said orbital arm, an earth-globe-carrying 115 plate, an earth-globe spindle mounted upon said plate, and concentric spindles respectively connected with said plate and the earth-globe spindle and actuated by said operating-spindle for simultaneous rotation in opposite 120 directions and with unequal speed to cause retrogression of the moon's nodes, substantially as specified.

31. A tellurian having a swinging orbital 125 arm, an operating-spindle mounted upon said arm, means for communicating rotary motion to said spindle, a reciprocatory traveler having swinging connection with the spindle of said orbital arm, an earth-globe-carrying plate, an earth-globe spindle mounted upon said plate, concentric spindles respectively connected 130 with said plate and the earth-globe spindle,

a motion-imparting gear carried by the operating-spindle, and motion-receiving gears carried respectively by said concentric spindles and meshing with the motion-imparting gear
5 at opposite sides, said motion-receiving gears having a differential number of teeth, substantially as specified.

In testimony that I claim the foregoing as my own I have hereto affixed my signature in the presence of two witnesses.

ALBERT M. BAKER.
